UNITED STATES PATENT OFFICE.

ARTHUR J. BAZELEY, OF CLEVELAND, OHIO, ASSIGNOR TO NATIONAL MALLEABLE AND STEEL CASTINGS COMPANY, OF CLEVELAND, OHIO, A CORPORATION OF OHIO.

CAR COUPLER.

Application filed September 11, 1924. Serial No. 737,034.

Fig. 1 is a central horizontal section of a car coupler embodying my invention showing the knuckle partly in section and with the knuckle in locked position; Fig. 2 is a 5 vertical section on the line 2—2 of Fig. 1; Fig. 3 is a view similar to Fig. 2 but with the lock in lock-set position; Fig. 4 is a view similar to Fig. 1 but with the knuckle in full lines and in knuckle thrown position; Fig. 5 is a central vertical section on the line 5—5 10 of Fig. 4, but with the knuckle being shown in elevation; Figs. 6 and 7 are perspective views of the lock lifter and lock, respectively; and Fig. 8 is a section similar to Fig. 2 15 but showing the application of a bottom operating lever for lifting the lock.

My invention relates to car couplers of the Master Car Builders' type, and particularly to car couplers of that type in which a spring 20 is employed to actuate or throw the knuckle. In my improved construction the knuckle throwing means is contained in the knuckle and I also employ a lock having improved locking, lock-setting and anti-creep means. 25 My invention also comprises the various features which I shall hereinafter describe and claim.

Referring to the drawings, A indicates a 30 coupler-head, B the knuckle, C the lock, and D the lifter.

The knuckle B is pivoted to the coupler-head in the usual manner by the pivot pin 2 and has to the rear of the pivot pinhole arc shaped pulling lugs 3 on top and bottom of 35 the knuckle tail which engage corresponding pulling bearings 4 on the top and bottom walls of the coupler cavity. The knuckle tail adjacent its locking face 5 has a bevelled portion 6 which inclines upwardly into a 40 raised transversely extending portion or hump 7, the purpose of which is to be later described.

The knuckle B has a cavity 8 extending horizontally about, and to the rear of, the 45 pivot pin hole, which is entered at 9 from the outer side of the knuckle. Seated in the cavity 8 is a spring 10 which at its inner end bears against an abutment 11 and at its outer end about a centering projection 12 on 50 the spring carrier 13. The carrier 13 has a central aperture through its hub 14 for the pivot pin, a surface 15 which bears against

the inner face of the side wall 16 of the 55 coupler head. The carrier also has a lug 17 which comes into bearing with the interior web or wall 18 inside of the knuckle tail. The carrier also has a curved surface 19 on the side of the carrier opposite the lug 17. The wall 20 in the knuckle engages the surface 19 and terminates in the surface 21 at 60 the forward end of the opening 9 in the knuckle.

In assembling the spring 10 and spring carrier 13 in the knuckle, the spring 10 is 65 first inserted into the cavity 8 with its inner end against the abutment 11. The spring carrier 13 is then passed through the opening 9 in such manner that the outer end of the spring lies between the centering projection 12 and the hub 14 of the carrier 13. As 70 soon as the surface 19 has passed inside the hump 21 on the wall 20 of the knuckle the carrier is rotated in a counter-clockwise direction until the lug 17 is swung around into contact with the web 18. The spring 10 is 75 then compressed and snapped over the projection 12 and will then come into bearing with the shoulder 22 on the projection 12, which is curved so that in the opening and closing movements of the knuckle the spring 80 10 will rock around the projection 12, thereby eliminating any substantial bending of the spring 10.

When the spring and spring carrier have 85 been assembled in the knuckle as just described they are automatically locked in place by the bearing of the lug 17 against the web 18 of the knuckle tail and by the curved surface 19 against the wall 20, and these parts are held in such position by the 90 pressure of the spring 10, which is under a substantial initial compression. The carrier 13 is thus held firmly in place so that if desired the knuckle, with spring 10 and carrier 13 in position therein, can be handled 95 and shipped as a single piece.

The lock C is comprised of a locking head 23 with a depending leg 24 and a forwardly projecting foot 25 and a lock-setting shoulder 26 at the heel of the foot. Between the head 23 and the foot 25 is a transversely extending recess 27 through which the knuckle tail swings in opening and closing and engages the under side of the head 23 of the 100

lock and thereby lifts the lock from its lock-set seat and carries it during opening and closing movements. Extending downwardly from the lock head 23 on the guard arm side 5 of the coupler is a projection 28 by which the lock is supported when in locked position. The lock C has on its rear side a vertically extending slot 29 intersected by a transversely arranged pin 30. Intersecting the 10 slot 29 is a groove 31 in the top surface of the lock which extends from the slot 29 to the forward edge of the lock. To prevent the removal of the lock from the coupler after the knuckle is in place, the foot 25 of the 15 lock is provided with a lateral projection 32 which lies beneath the knuckle tail in all positions of the knuckle tail, and thereby limits the upward movement of the lock.

The lifter has a depending arm 33 which 20 seats in the slot 29 and has near its lower end a rearwardly facing recess 34 to engage the pin 30. Extending forwardly along the underside of the lifter is a rib 35 intended to fit into the groove 31 in the top 25 of the lock. When the lock is in locked position, as is shown in Fig. 2, the lock is supported by the bearing of its projection 28 on the ledge 36 of the coupler-head, the slope of which is such as to cause the foot 25 of the lock to swing forwardly under the ledge 36. In such position the engagement 30 of the foot against the under surface 36^a of the ledge 36 will prevent the lock from creeping. As soon as the lock is raised by 35 the lock lift D the leg 24, because the pivotal connection between lock C and lifter D is at the rear side of the lock, will swing rearwardly to such an extent that the foot 25 will clear the anti-creep surface 36^a and 40 the lock C will then be in a position to be lifted vertically. As the lock is further lifted the weight of the lock will tilt the leg 24 rearwardly until the lock-set shoulder 26 is directly above the lock-set seat 37 45 at the rear of the lock hole. If the lifter is then released the lock will then drop down to lock-set position with the shoulder 26 on the seat 37.

To hold the lock against tipping rearwardly or toward one side, when it is being lifted, the rib 38 extends downwardly from the top wall of the coupler-head, while the inner front face 39 of the coupler-head and the side wall 40 of the lock hole also serve to 50 guide it and hold it from movement forwardly or toward the other side.

When the lock has been lifted to either lock-set or knuckle thrown positions, as are 55 shown in Figs. 3 and 5 respectively, the knuckle is then free to open and the pressure of the surface 15 of the carrier 13 against the face 16 of the coupler-head caused by the spring 10 forces the knuckle tail to swing outwardly through the recess 27 in the forward face of the lock C. As the knuckle

tail swings outwardly its hump 7 lifts the lock, and if the lock is in lock-set position lifts it from such position, and carries it on the knuckle tail by its engagement with the under side of the lock head during the 70 opening and closing movement of the knuckle.

When the knuckle is again closed the lock drops to locked position shown in Fig. 2.

In Fig. 8 I have shown my invention employed with a bottom operated lifter or lever D' in which the lifter has a recess 34' which engages the pin 30' just as in the top operated form. The lock is operated by an actuating mechanism (not shown) connected to the lifter through the aperture 41. The lock in all of its movements operates identically with the top operated form.

The terms and expressions which I have employed are used as terms of description 85 and not of limitation, and I have no intention, in the use of such terms and expressions, of excluding any mechanical equivalents of the features shown and described, or portions thereof, but recognize that various 90 structural modifications are possible within the scope of the invention claimed.

What I claim is:

1. A car coupler of the Master Car Builders' type having a spring actuated knuckle 95 and a vertically movable lock, the knuckle having a spring carrier mounted on the pivot pin, a spring mounted between the carrier and a portion of the knuckle, the carrier having a bearing on the coupler-head 100 and being movable relative to both coupler and knuckle.

2. A car coupler of the Master Car Builders' type having a spring actuated knuckle 105 and a vertically movable lock, the knuckle having a spring carrier mounted on the pivot pin, a spring mounted between the carrier and a portion of the knuckle, the carrier having a rotative bearing in the knuckle and a surface engaging the coupler-head. 110

3. A car coupler of the Master Car Builders' type having a spring actuated knuckle 115 and a vertically movable lock, the knuckle having a cavity therein for a spring carrier and a spring, the spring carrier being capable, under impulse of the spring, of movement relative to the knuckle and having a fulcrum bearing on the coupler head.

4. A car coupler of the Master Car Builders' type having a spring actuated knuckle 120 and a vertically movable lock, the knuckle having a cavity therein for a spring carrier and a spring, the spring carrier being capable, under impulse of the spring, of movement relative to the knuckle and having a fulcrum bearing on the coupler head, 125 the carrier having bearings on the knuckle to limit the movement of the carrier and spring relative to the knuckle.

5. A car coupler of the Master Car Build-

ers' type having a rotative knuckle and a vertically movable lock, spring mechanism for actuating the knuckle comprising a spring carrier and a spring, the spring being under compression between a portion of the knuckle and the carrier and the carrier being mounted in the knuckle and capable

of movement relative thereto, the carrier having a fulcrum bearing on the coupler-head whereby the compression of the spring ¹⁰ forces the knuckle into open position, and retaining means for spring and carrier.

ARTHUR J. BAZELEY.
